HAND-OPERATED FOOD MIXER

Clarence E. Elliott, Kansas City, Kans.

Application April 20, 1953, Serial No. 24,584

Term of patent 14 years

(Cl. D44—1)

To all whom it may concern:

Be it known that I, Clarence E. Elliott, a citizen of the United States, residing at Kansas City, in the county of Wyandotte and State of Kansas, have invented a new, original, and ornamental Design for a Hand-Operated Food Mixer, of which the following is a specification, reference being had to the accompanying drawing, forming a part thereof.

Fig. 1 is a front elevational view of a hand-operated food mixer, showing my new design.

Fig. 2 is a side elevational view thereof; and
Fig. 3 is a top plan view thereof.

I claim:

The ornamental design for a hand-operated food mixer, as shown.

CLARENCE E. ELLIOTT.
